ELECTRIC CIRCUIT BREAKER

Gustav E. Jansson, North Quincy, Mass., assignor
to Allis-Chalmers Manufacturing Company,
Milwaukee, Wis., a corporation of Delaware

Application June 10, 1940, Serial No. 339,598

16 Claims. (Cl. 200—148)

This invention relates in general to improvements in electric circuit breakers and more particularly to means for increasing the current carrying capacity and the interrupting ability of circuit breakers of the fluid blast type.

Circuit breakers of the fluid blast type, especially those of the air blast type, are well adapted to interrupt relatively large currents in a very short length of time. To obtain a fast interrupting operation the movable elements of the circuit breaker are generally made as light as possible, sometimes providing only abutting arcing contacts for the flow of current through the circuit breaker. These contacts become burnt during current interrupting operation of the circuit breaker and accordingly may offer a relatively high resistance to the flow of current therethrough.

It is therefore desirable to provide main or current carrying contacts in parallel with the arcing contacts and to mount the movable main contact resiliently on the movable arcing contact. In this manner the two sets of contacts may be sequentially operated by common actuating means without excessive increase in the weight of the movable members of the circuit breaker. The arcing chamber and the contacts should be so shaped as to define a nozzle gradually converging toward the arcing surfaces of the arcing contacts.

With this arrangement the air blast rapidly transfers the arc from the arcing contacts to arcing electrodes provided therefor, thereby reducing the burning at the arcing contacts. Material vaporized from the arcing contacts is also driven away from the main contacts which are thus protected against deterioration. The arc is preferably directed against nested baffles associated with an electrode connected with one of the contacts through a resistor to shunt a portion of the arc and thereby to cause its extinction.

It is therefore one of the objects of the present invention to provide a circuit breaker of the fluid blast type in which current is normally conducted by contacts other than the contacts at which the current is interrupted.

Another object of the present invention is to provide a circuit breaker of the fluid blast type facilitating the transfer of current from the main contacts to the arcing contacts.

Another object of the present invention is to provide a circuit breaker of the fluid blast type in which the velocity of the fluid blast gradually

increases to a maximum value as the fluid progresses towards the arcing contacts.

Another object of the present invention is to provide a circuit breaker of the fluid blast type in which the arc is extinguished by the combined action of nested baffles and of a resistive shunt.

Objects and advantages other than those above set forth will be apparent from the following description when read in connection with the accompanying drawings, in which:

Fig. 1 is a view partly in elevation and partly in cross section of one embodiment of the present invention comprising a horizontally disposed arcing chamber;

Fig. 2 is an axial cross section through the arcing chamber of the embodiment illustrated in Fig. 1 showing the main and arcing contacts of the circuit breaker in the closed position;

Fig. 3 is a view similar to Fig. 2 showing the contacts in the open position;

Fig. 4 is an end view of the movable arcing contact of the embodiment illustrated in Fig. 1;

Fig. 5 is an end view of the stationary main and arcing contact assembly of the embodiment illustrated in Fig. 1;

Fig. 6 is a partial cross section through a modification of the arc extinguishing chamber of the embodiment illustrated in Fig. 1;

Fig. 7 is a view in side elevation of a modified embodiment of the present invention comprising a vertically disposed arcing chamber;

Fig. 8 is an axial cross section through the arcing chamber and the arc extinguishing chamber of the embodiment illustrated in Fig. 7 showing the main and arcing contacts of the circuit breaker in the open position;

Fig. 9 is an axial cross section through the arcing chamber of another modified embodiment of the present invention in which the main contacts are disposed outside of the arcing chamber, all the contacts of the circuit breaker being shown in the closed position; and

Fig. 10 is a view similar to Fig. 9 showing all the contacts of the circuit breaker in the open position.

Elements performing the same function in these different embodiments are designated therein by the same reference character although such elements may be of different configuration in the different embodiments shown.

Referring more particularly to the drawings by characters of reference, reference numeral 11 designates a reservoir serving both as structural element and as source of supply of fluid under pressure for the circuit breaker. The fluid uti-

lized may be any of the insulating fluids suitable for extinguishing arcs but will be assumed to be compressed air preferably maintained at a pressure of the order of 135 to 215 pounds per square inch. Reservoir 11 may be placed in communication with a hollow cylinder 12 defining an arcing chamber 13 through a valve 14 and through a hollow insulator 16. The flow of fluid from reservoir 11 to atmosphere continues from arcing chamber 13 through an orifice 17 of the arcing chamber and through an arc extinguishing chamber 18. Chamber 18 is generally defined by an elbow 19 of conductive material having a substantially uniform cross section and by a cylinder 20 of insulating material.

Valve 14 is preferably operated by means of a pneumatic motor 21 adapted to be supplied with air from reservoir 11 through a valve 22 controlled by a solenoid 23. When valve 14 is open air is also supplied therethrough to a second air motor 24 serving to open a movable disconnecting contact 26 cooperating with a fixed disconnecting contact 27. Contact 26 may be reclosed by a third pneumatic motor 28 connected with reservoir 11 through a valve 29 controlled by a solenoid 30. The circuit controlled by the circuit breaker is assumed to be an alternating current circuit represented by two sections of conductors 31 which are joined through disconnecting contacts 26, 27 in series with the main and arcing contacts of the circuit breaker.

As illustrated in Figs. 2 and 3 the arcing chamber is provided with a pair of cooperating main contacts 32, 33. Contact 32 is a fixed annular contact comprising a plurality of segments resiliently mounted on a conductive annular contact support 34. Support 34 is bounded by a plurality of intersecting surfaces including a plane surface 36 and a cylindrical surface 37. The segments of contact 32 are arranged about cylindrical surface 37 to define a concave contact surface of revolution 38 for resilient sliding engagement of contact 33 with contact 32. The contact segments are pivotally mounted on support 34 and are resiliently urged against cylindrical surface 37 by springs 39 held by screws 40. An insulating liner 41 prevents screws 40 from working loose from support 34 under the action of vibration.

Contact 33 is a cylindrical movable contact coaxial with contact 32 and is bounded by a plurality of intersecting surfaces including a plane surface 42 and a cylindrical surface 43. Contact 33 is provided with an extension 44 forming a hollow piston rod rigidly connected with a piston 46 carrying contact 27. Piston 46 is arranged for reciprocatory movement within a cylinder 47 communicating with arcing chamber 13 and mounted on cylinder 12 through an insulating bushing 48. A spring 49 moves contact 33 toward contact 32 to cause sequential sliding engagement of surface 43 with surface 38 and abutting engagement of surface 42 with surface 36. The movement of contact 33 into the closed position thereof is thus limited independently of the fixed main and arcing contacts of the circuit breaker. Contacts 32, 33 are adapted to be separated by means of piston 46 under the action of the air pressure within the arcing chamber and cylinder 47. The air pressure exerted on contact 33 in the closing direction thereof is balanced by admitting air within contact 33 from chamber 13 through apertures 50.

Contacts 32, 33 are connected in parallel with a pair of cooperating arcing contacts 51, 52 arranged within the arcing chamber and operable

to close orifice 17. Contact 51 is an annular fixed contact arranged about orifice 17 coaxially with contact 32 and connected therewith through support 34. Contact 52 is mounted on a stud 53 slidably supported within piston rod 44. A spring 54 arranged between contact 33 and a lock nut 55 screwed on stud 53 tends to separate contacts 33 and 52 to an extent limited by a stop 57. Contact 52 is thus resiliently supported on contact 33 and piston 46 serves as common means for sequentially separating contacts 32, 33 and contacts 51, 52.

Relatively movable contacts 33, 52 are connected by a plurality of flexible conductors 58 reinforced and joined at both ends by riveted washers 59. Spring 54, which maintains contacts 33, 52 in predetermined relative position, acts on the contacts through the end portions of conductors 58 to clamp the conductors against the contacts in conductive relation therewith. The arcing surface of contact 52 cooperating with the complementary surface of contact 51 is provided with grooves 60 for permitting the passage of air under pressure from chamber 13 into chamber 18 prior to separation of contacts 51, 52.

Contact 52 is provided with an arcing electrode 61 arranged coaxially with orifice 17 and to which the arc is to be transferred upon separation of contacts 51, 52. Electrode 61 may be made of any difficultly fusible conductive material such as tungsten. To provide rapid transfer of the arc to the arcing electrode the portion of the arcing chamber adjacent the cooperating surfaces of contacts 51, 52 is arranged to form a gradually converging nozzle by proper dimensioning of the arcing chamber and of the main and arcing contacts and by suitable positioning of the contacts within the chamber. The path for the flow of compressed air from reservoir 11 to atmosphere comprises this nozzle, which has preferably its smallest cross section defined by the cooperating surfaces of the arcing contacts regardless of the extent of opening of the contacts. Even when contacts 51, 52 are fully open, the cross-section area of the passage defined by their cooperating surfaces is preferably smaller than the cross-section area of aperture 17.

A second arcing electrode 62 is arranged within chamber 18 substantially axially thereof. Electrode 62 is supported on a pair of conductive spiders 63 mounted on insulating cylinder 20 and is connected with contact 33 through a resistor 64 and through a conductor 65 comprising a flexible portion. As more clearly illustrated in Fig. 8 resistor 64 consists of two parallel wires of suitable resistive material wound in two layers on cylinder 20. These two wires are wound in opposite directions so as to render the resistor substantially non-inductive. A shield 66 is arranged adjacent a portion of the surface of cylinder 20 to prevent deposition of material vaporized from contacts 51, 52 on the shielded portion of cylinder 20. In this manner a conductive path cannot be established between electrode 62 and contact 51 through material deposited on the wall of cylinder 20. A plurality of coaxial conductive baffles 67 are disposed about the upper portion of electrode 62 to cool and deionize the air blast discharge from chamber 18 to atmosphere.

In operation, the circuit breaker being closed as illustrated in Figs. 1 and 2, current flows between conductors 31 through the wall of cylinder 12, main contacts 32, 33 and disconnecting contacts 27, 26. Although the arcing contacts are

closed in parallel with the main contacts, the flow of current will generally pass almost entirely through the main contacts because of the relatively small area of the cooperating surfaces of the arcing contacts and of their burning by the arc.

When the circuit breaker is to be opened, solenoid 23 is energized from a suitable source of current (not shown) to cause actuation of valve 22. The valve admits compressed air from reservoir 11 to motor 21, which opens the blast valve 14. Air under pressure is then supplied from reservoir 11 through valve 14 to arcing chamber 13 and to motor 24. While the air pressure within the arcing chamber builds up to the pressure of reservoir 11, air is leaking through apertures 50 and past contacts 51, 52 through grooves 60, thereby giving an initial acceleration to the air column contained within the arc interrupting chamber.

When the air pressure within the arcing chamber and within cylinder 41 reaches a sufficient value, piston 46 is moved toward the right against the action of spring 49. Movement of piston 46 first separates main contacts 32, 33 while spring 54 maintains arcing contact 52 applied against contact 51. Upon separation of the main contacts the flow of current is diverted from the main contacts to the arcing contacts against the action of the resistive voltage drop in the arcing contacts and against an inductive voltage due to the rate of change of the flow of current through the connections between the main and arcing contacts. The relative positioning of the main and arcing contacts in coaxial relation limits the inductance of the connections therebetween to an extremely low value so that the inductive voltage appearing across the main contacts upon separation thereof is negligibly small. In addition, the main contacts are then separated by a gap in air at substantially the full pressure of reservoir 11, which has dielectric properties comparable to those of high grade insulating oil. For these two reasons the transfer of the flow of current to the arcing contacts takes place without any arcing at the main contacts, which are thus protected from burning.

When piston 46 reaches a predetermined position, hollow rod 44 engages stop 57 to move contact 52 jointly with contact 33. Contacts 51, 52 are thereby separated and an arc is drawn therebetween while a blast of air is projected from the arcing chamber into the arc extinguishing chamber through orifice 17. Contacts 33, 52 finally reach the position shown in Fig. 3 of the drawings, the gap between contacts 51, 52 being preferably of the order of one-half inch. As a result of the arrangement of the arcing chamber and of the contacts forming a converging nozzle, the velocity of the air blast is maximum between the cooperating surfaces of the arcing contacts while substantially the full pressure of reservoir 11 is maintained within the space separating the main contacts. The air blast may establish itself at maximum velocity without appreciable delay as the column of air contained within chamber 18 is already set in motion by the air previously passing through grooves 60 of contact 52. Material vaporized by the arc from the arcing contacts is directed by the air blast away from the main contacts through orifice 17, thereby preventing injurious deposition of vaporized material on the contact surfaces of the main contacts.

The air blast issuing from the arcing chamber between contacts 51 and 52 drives the arc toward chamber 18. The root of the arc on contact 52 is displaced on the surface of the contact until it is transferred to arcing electrode 61. The other root of the arc on contact 51 moves along the bore of contact 51 and on the inner surface of elbow 19 until it is prevented from progressing further by shield 66. The arc also gradually lengthens as its roots are displaced. The portion of the arc attached to electrode 61 is guided towards the axis of chamber 18 by the air blast, which is radial between electrodes 51 and 52. The arc therefore rapidly comes in contact with electrode 62, whereupon it breaks into two portions. A first arc portion extends between electrodes 61 and 62 along the axis of chamber 18. The second portion extends between electrode 62 and elbow 19 and is displaced by the air blast to extend between elbow 19 and the lower spider 63.

The first arc portion is located in a zone where the air issuing from chamber 13 at maximum velocity suddenly expands to substantially atmospheric pressure with a corresponding large drop in temperature. The incandescent ionized air in the arc path is therefore replaced at a rapid rate by cold non-ionized air, thereby rendering the continuous ionization of the arc path possible only as long as the arc current remains of relatively high intensity. This portion of the arc path is shunted by resistor 64, which likewise connects electrode 61 with electrode 62.

When the flow of current through the circuit breaker decreases toward the end of the first half cycle of arcing, the rate of ionization of the arc path by the current gradually decreases. The ionization rate of the arc path between electrodes 61 and 62 ultimately becomes lower than the rate of deionization of the arc path by the air blast. The arc between electrodes 61, 62 therefore extinguishes, the current then flowing through the circuit breaker through cylinder 12, elbow 19, the remaining second arc portion, electrode 62 and baffles 67, resistor 64, conductor 65, contact 27 and contact 26. This current is limited to a relatively low value by resistor 64. The resistance of resistor 64 is of relatively high value compared to the inductance of circuit 31, so that the current is substantially in phase coincidence with the voltage of the circuit. This current dissipates the magnetic energy stored in the circuit 31 by reason of the inductance thereof.

When the voltage reaches the value zero the remaining arc is easily extinguished by the air blast. The voltage thereupon reverses and follows its normal wave without presenting the over-voltages that would result from a current interruption omitting the discharge of the stored energy of the circuit. The gaps between contacts 32, 33 and between contacts 51, 52 are filled with compressed air of high insulating value and the path of the arc between electrodes 61 and 62 has been fully deionized by the air blast while the current was flowing by way of resistor 64. There is accordingly no tendency for the spaces between the contacts and between the electrodes to break down to form a new arc. The arc path between elbow 19 and baffles 67, which carried the low current of resistor 64, is deionized so rapidly that ignition of a new arc thereat is also prevented. The air blast carrying the heat dissipated in the arc is cooled and substantially deionized by means of baffles 67.

During the above described operation, motor

24 receives air from reservoir 11 through valve 14. The cross section of the air passage between motor 24 and valve 14 and the inertia of the moving parts driven by the motor are so selected that contact 26 is separated from contact 27 when the main and arcing contacts are open and within a few cycles from the interruption of the arc. When contact 26 is fully open, solenoid 23 is preferably deenergized by any suitable known interlock (not shown) to cause reclosure of valve 14. Upon closure of valve 14 chamber 13 gradually returns to atmospheric pressure and spring 49 returns contacts 33, 52 to the position shown in Fig. 2. Contact 52 enters into abutting engagement with contact 51 when contacts 32, 33 are still open a predetermined distance less than the maximum opening thereof. Contact 33 thereafter enters into resilient sliding engagement with contact 32 and finally into abutting engagement with member 34.

To reclose the circuit breaker, solenoid 30 is momentarily energized to actuate valve 29. The valve admits air from reservoir 11 to motor 28 which returns contact 26 to the closed position. The entire circuit breaker is then returned to the position shown in Figs. 1 and 2.

In the embodiment partially illustrated in Fig. 6 electrode 62 is surrounded by a nested plurality of short annular conductive baffles 68, 69, 70. Baffles 69, 70 are separated by an insulating baffle 71 extending therefrom toward orifice 17. Contact 51 is provided with a plurality of ports 12 for projecting auxiliary air blasts into chamber 18 about contact 51.

The operation of the present embodiment is generally similar to that of the embodiment illustrated in Fig. 1. An arc is drawn between contacts 51, 52, one of its roots is transferred to arcing electrode 61 and the other root is displaced along the bore of contact 51 and of elbow 19. A number of successive approximate positions of the arc during the interrupting process are shown in dotted line in Fig. 6 to clarify the explanation of the circuit breaker operation. The auxiliary air blasts projected through ports 12 cooperate with the main blast projected through the bore of contact 51 to maintain the greater portion of the arc axially of chamber 18, causing it to come in contact with electrode 62. The arc is thereupon divided into a plurality of portions including a portion 73 extending between electrodes 61 and 62 and another portion 74 extending from electrode 62 to the wall of elbow 19. The latter portion in turn is urged by the air blast against baffle 71 and is ultimately divided into a portion 76 extending between baffles 69, 70 and looped over baffle 71, and a portion 77 extending between baffle 68 and elbow 19. The arc portions 73 and 76, 77 are sequentially extinguished in the manner above set forth with respect to the embodiment illustrated in Fig. 1.

The embodiment illustrated in Figs. 7 and 8 differs from the embodiment illustrated in Fig. 1 mainly in that reservoir 11 has been rotated by 90 degrees to bring arcing chamber 13 in vertical alignment with baffle 67. Cylinder 20 is accordingly mounted directly on cylinder 12 without interposition of an elbow. As illustrated in Fig. 8 the elements contained within chambers 13 and 18 are generally similar to those illustrated in Figs. 2 and 3. In the present embodiment however contact 33 is rendered resilient by the provision of a plurality of saw cuts along the periphery thereof. Contact 33 engages the top 75

wall of cylinder 12, which serves as fixed main contact.

The embodiment partially illustrated in Figs. 9 and 10 differs from the embodiment illustrated in Fig. 1 in that the main contacts are removed from the arcing chamber, which contains only arcing contacts 51, 52. Contact 52 is rigidly connected with piston 46 instead of being connected therewith through a spring. Cooperating movable main contacts 78, 79 are provided for bridging arcing contacts 51, 52 as well as disconnecting contacts 26, 27. Contact 78 is preferably a laminated contact pivotally mounted at 80 on a conductive extension of cylinder 12. Contact 78 is adapted to be moved to open position by means of a piston 81 movable within a cylinder 82 against the action of a spring 83. The mechanism connecting contact 78 with piston 81 is preferably of the toggle type to obtain a relatively high pressure between contacts 78 and 79. Cylinder 82 communicates with chamber 13 through a port 84. The walls of cylinders 82 and 12 define a passage 86 for connecting cylinder 47 with cylinder 82 when piston 81 is near the top of its stroke. Cylinder 47 is otherwise without connection with arcing chamber 13. Contact 79 is integral with contact 26 but is so arranged that contact 26 engages contact 77 before contact 79 can engage contact 78.

In operation, the circuit breaker contacts being in the position shown in Fig. 9, the flow of current between conductors 31 takes place through contacts 78, 79, which offer the path of least resistance between the conductors. Upon actuation of valve 14 arcing chamber 13 is filled with air under pressure from reservoir 11 as in the embodiment illustrated in Fig. 1. The air flows from chamber 13 into cylinder 82 through port 84 to cause upward movement of piston 81. The piston moves contact 78 to open position to separate contacts 78, 79. The flow of current is then transferred to arcing contacts 51, 52 in series with disconnecting contacts 26, 27 and this transfer is effected without arcing at the main contacts because of the low inductance of the connections between the main and arcing contacts.

When piston 81 is near the top of its stroke it uncovers passage 86, which connects cylinder 47 with cylinder 82. Air under pressure then flows from cylinder 82 into cylinder 47 to cause actuation of piston 46 toward the right. Piston 46 separates arcing contacts 51, 52 to draw an arc therebetween. The arc is transferred to the arcing electrodes and is extinguished in the manner above set forth with respect to the embodiment illustrated in Fig. 1. After a predetermined time delay depending on the dimensions of motor 24 and of contacts 26, 79, the latter contacts are jointly moved toward open position by motor 24. Contact 79 is moved away from closed position while contact 26 still engages contact 77, and continued movement of contacts 78, 26 separates the disconnecting contacts. The different contacts of the circuit breaker then reach the position illustrated in Fig. 10. Upon reclosure of valve 14 the arcing chamber returns to atmospheric pressure and the air pressure is also released from cylinders 47 and 82. Spring 49 recloses arcing contacts 51, 52 and spring 83 returns contact 78 to closed position.

To reclose the circuit breaker, current is admitted to solenoid 30 which actuates valve 29 and air under pressure is admitted from reservoir

11 to motor 28. Contacts 79, 26 are jointly moved by motor 28 toward closed position but the arrangement of the contacts causes reclosing of disconnecting contacts 26, 27 before contact 79 is returned to closed position into engagement with contact 78.

Although but a few embodiments of the present invention have been illustrated and described it will be apparent to those skilled in the art that various changes and modifications may be made therein without departing from the spirit of the invention or from the scope of the appended claims.

It is claimed and desired to secure by Letters Patent:

1. An electric circuit breaker comprising an arcing chamber having an orifice, a pair of cooperating arcing contacts arranged within said chamber and operable substantially to close said orifice, a source of fluid under pressure, means comprising a wall of said chamber and said contacts for defining a gradually converging nozzle ending at said passage, and means defining a path for the flow of fluid from said source to atmosphere comprising said nozzle and said passage, said path having its smallest cross section area at said passage, whereby the fluid pressure within said nozzle is substantially the full pressure of said source and the velocity of said flow of fluid is maximum between the cooperating surfaces of said contacts during opening operation of the circuit breaker.

2. An electric circuit breaker comprising an arcing chamber having an orifice, a pair of cooperating arcing contacts arranged within said chamber and operable substantially to close said orifice, a pair of cooperating main contacts arranged within said chamber and connected in parallel with said arcing contacts, means for separating said main contacts and for thereafter separating said arcing contacts, a source of fluid under pressure, means comprising the dimensioning of said chamber and of said contacts and the positioning of said contacts within said chamber for defining a gradually converging nozzle ending at the cooperating surfaces of said arcing contacts, and means for directing material vaporized from said arcing contacts during opening operation of the circuit breaker away from said main contacts through said orifice comprising means defining a path for the flow of fluid from said source through said nozzle and said orifice to atmosphere.

3. An electric circuit breaker comprising an arcing chamber having an orifice, a pair of cooperating arcing contacts arranged within said chamber and operable substantially to close said orifice, a pair of cooperating main contacts arranged within said chamber and connected in parallel with said arcing contacts, means for separating said main contacts and for thereafter separating said arcing contacts, a source of fluid under pressure, means defining a path for the flow of fluid from said source through said circuit breaker to atmosphere, and means for preventing arcing between said main contacts upon separation thereof comprising a gradually converging nozzle defined within said chamber by the walls of said chamber and by said contacts, said nozzle forming a part of said path ending at the cooperating surfaces of said

arcing contacts, whereby the fluid pressure within the space between said main contacts is substantially the full pressure of said source during opening operation of the circuit breaker.

4. An electric circuit breaker comprising an arcing chamber having an orifice, an annular fixed contact arranged about said orifice, a movable contact arranged within said chamber cooperating with said annular contact, an arcing electrode mounted on said movable contact coaxially with said orifice, a pair of cooperating main contacts arranged within said chamber and connected in parallel with said arcing contacts, means comprising the dimensioning of said chamber and of said contacts and the positioning of said contacts within said chamber for defining a gradually converging nozzle ending at the cooperating surfaces of said arcing contacts, means for sequentially separating said main contacts and separating said arcing contacts to draw an arc therebetween, and means for transferring said arc from said movable arcing contact to said electrode comprising means defining a path for the flow of fluid from said source through said nozzle and through said orifice to atmosphere.

5. An electric circuit breaker comprising an arcing chamber having an orifice, a fixed annular arcing contact arranged about said orifice, a movable arcing contact arranged within said chamber and operable substantially to close said orifice, a fixed annular main contact arranged coaxially with said annular arcing contact and connected therewith, a movable annular main contact arranged about said movable arcing contact coaxially therewith and connected therewith, means for separating said main contacts and for thereafter separating said arcing contacts to transfer the flow of current from said main contacts to said arcing contacts and to draw an arc between said arcing contacts, a source of fluid under pressure, means comprising the dimensioning of said chamber and of said contacts and the positioning of said contacts within said chamber for defining a gradually converging annular nozzle ending at the cooperating surfaces of said arcing contacts, and means for preventing burning of said main contacts during opening operation of the circuit breaker comprising the relative positioning of said main and arcing contacts to limit the inductance of the connections between said contacts to a relatively low value and means defining a path for the flow of fluid from said source through said nozzle and through said orifice to atmosphere.

6. An electric circuit breaker comprising a pair of relatively movable conductive members, a flexible conductor for interconnecting said members, a resilient member acting on the first said members through different portions of said conductor to clamp said conductor against the first said members in conductive relation therewith, and stop means on the first said members for limiting the relative movement of the first said members under the action of said resilient member.

7. An electric circuit breaker comprising an annular conductive member bounded by intersecting plane and cylindrical surfaces, a plurality of contact segments arranged about said cylindrical surface to define a concave contact surface of revolution, means for pivotally mounting said segments on said member and for resiliently urging said segments against said cylindrical surface, a cylindrical contact coaxial with said

member bounded by intersecting plane and cylindrical surfaces, and means for moving said cylindrical contact toward said member to cause sequential sliding engagement of the cylindrical surface of said cylindrical contact with the concave surface of said segments and abutting engagement of the plane surface of said cylindrical contact with the plane surface of said member.

8. An electric circuit breaker comprising a pair of cooperating arcing contacts, a pair of cooperating disconnecting contacts serially connected with said arcing contacts, cooperating main contacts for bridging said arcing and disconnecting contacts, one of said main contacts being integral with one of said disconnecting contacts, and means for sequentially opening said main, arcing, and disconnecting contacts.

9. An electric circuit breaker comprising a pair of cooperating arcing contacts, a pair of cooperating disconnecting contacts serially connected with said arcing contacts, cooperating movable main contacts for bridging said arcing and disconnecting contacts, and means for sequentially moving one of said main contacts to open position, separating said arcing contacts, moving the other one of said main contacts toward open position and separating said disconnecting contacts.

10. An electric circuit breaker comprising a pair of cooperating arcing contacts, a pair of cooperating disconnecting contacts serially connected with said arcing contacts, cooperating first and second movable main contacts for bridging said arcing and disconnecting contacts, means for causing opening of the circuit breaker comprising means for sequentially moving said first main contact to open position, separating said arcing contacts, moving said second main contact toward open position, separating said disconnecting contacts, reclosing said arcing contacts and returning said first main contact to closed position, and means for causing closing of the circuit breaker comprising means for sequentially reclosing said disconnecting contacts and returning said second main contact to closed position.

11. An electric circuit breaker comprising an arcing chamber having an orifice, an arc extinguishing chamber communicating with said arcing chamber through said orifice, a pair of cooperating arcing contacts arranged within said chamber, an electrode arranged within said arc extinguishing chamber and connected with one of said contacts, insulating means for supporting said electrode within said arc extinguishing chamber in insulated relation with the other one of said contacts, means for separating said contacts to draw an arc therebetween, means for projecting a blast of fluid under pressure from said arcing chamber through said orifice to cause transfer of said arc to said electrode and to cause extinction of said arc, whereby material vaporized from said contacts is deposited on said insulating means, and shield means adjacent a portion of the surface of said insulating means to prevent deposition of said material on said portion of the surface of said insulating means, thereby preventing formation of a conductive path between said electrode and said other one of said contacts by way of said material.

12. A circuit breaker comprising cooperating arcing contacts, one of said contacts being a hollow contact, means for projecting a blast of fluid under pressure through said hollow contact to extinguish an arc drawn between said contacts.

5 a resistor, means comprising an electrode in the path of said arc at a predetermined distance from said hollow contact for connecting said resistor between said contacts, said electrode being arranged axially in the discharge path of said blast, and a plurality of conductive partitions at a common potential arranged about said electrode at a distance from said hollow contact greater than said predetermined distance dividing the discharge path of said blast carrying the arc drawn between said electrode and said hollow contact.

10 13. An electric circuit breaker comprising an arcing chamber having an orifice, an arc extinguishing chamber communicating with said arcing chamber through said orifice, an annular fixed contact arranged about said orifice, a movable contact arranged within said arcing chamber, an electrode arranged within said arc extinguishing chamber at a predetermined distance from said orifice, a resistor connecting said electrode with said movable contact, means for separating said contacts to draw an arc therebetween, a plurality of coaxial conductive baffles at a common potential arranged about said electrode in said arc extinguishing chamber at a distance from said orifice greater than said predetermined distance, and means comprising a source of fluid under pressure for projecting a blast of fluid from said arcing chamber through said orifice into said arc extinguishing chamber, said blast intersecting the path of said arc between said contacts to cause transfer of a portion of said arc to another path between said electrode and said fixed contact, said blast also intersecting the second said arc path to drive said arc toward said baffles.

15 14. An electric circuit breaker comprising an arcing chamber having an orifice, an arc extinguishing chamber communicating with said arcing chamber through said orifice, an annular fixed contact arranged about said orifice, a movable contact arranged within said arcing chamber, an electrode arranged within said arc extinguishing chamber, a resistor connecting said electrode with said movable contact, means for separating said contacts to draw an arc therebetween, baffle means arranged adjacent said electrode comprising a pair of conductive baffles separated by an insulating baffle extending therefrom toward said orifice, and means comprising a source of fluid under pressure for projecting a blast of fluid from said arcing chamber through said orifice into said arc extinguishing chamber, said blast causing said arc to be displaced and divided into a plurality of serially connected portions including a portion extending between said movable contact and said electrode and another portion extending between said conductive baffles and looped over said insulating baffle.

20 15. An electric circuit breaker comprising an arcing chamber having an orifice, an arc extinguishing chamber communicating with said arcing chamber through said orifice, an annular fixed contact arranged about said orifice, a movable contact arranged within said arcing chamber to cooperate with said fixed contact, means for separating said contacts to draw an arc therebetween, means for projecting a blast of fluid under pressure from said arcing chamber through said orifice to drive said arc into said extinguishing chamber, and means for guiding said arc toward the axis of said extinguishing chamber comprising means for projecting auxiliary blasts of fluid into said extinguishing chamber about said annular contact.

16. A circuit breaker comprising a fixed main contact, a movable main contact, means for urging said movable main contact into engagement with said fixed main contact, means for separating said main contacts, a fixed arcing contact, a movable arcing contact resiliently mounted on said movable main contact to engage and disengage said fixed arcing contact when said movable main contacts are open at a distance less than the maximum opening there-

10

of, means comprising a source of fluid under pressure for directing a blast of arc extinguishing fluid on said arcing contacts, and means for preventing opening of said arcing contacts before opening of said main contacts comprising means for guiding said blast to cause said blast to urge said movable arcing contact toward engagement with said fixed arcing contact.
